(57) **CLAIM**

The ornamental design for a sealing tab, as shown and
described.

DESCRIPTION

FIG. 1 is a plan view of the top of a first embodiment of a
sealing tab wherein the top and the bottom are symmetrical,
and wherein the sealing tab is substantially transparent and
substantially planar.

FIG. 2 is a front perspective view thereof wherein the rear
is symmetrical.

FIG. 3 is a right side perspective view thereof wherein the
left side is symmetrical.

FIG. 4 is a plan view of the top of a second embodiment of
a sealing tab wherein the top and the bottom are symmetri-
cal, and wherein the sealing tab is substantially transparent
and substantially planar.

FIG. 5 is a front perspective view thereof.

FIG. 6 is a rear perspective view thereof.

FIG. 7 is a left side perspective view thereof.

FIG. 8 is a right side perspective view thereof.

FIG. 9 is a plan view of the top of a third embodiment of a
sealing tab wherein the top and the bottom are symmetrical,
and wherein the sealing tab is substantially transparent and
substantially planar.

FIG. 10 is a front perspective view thereof wherein the rear
is symmetrical.

FIG. 11 is a right side perspective view thereof wherein the
left side is symmetrical.

FIG. 12 is a plan view of the top of a fourth embodiment of
a sealing tab wherein the top and the bottom are symmetri-
cal, and wherein the sealing tab is substantially transparent
and substantially planar.

FIG. 13 is a front perspective view thereof.

FIG. 14 is a rear perspective view thereof.

FIG. 15 is a left side perspective view thereof; and,

FIG. 16 is a right side perspective view thereof.
